UNITED STATES PATENT OFFICE.

WILLIAM HENRI POOLE, OF PORTLAND, OREGON.

INDICATOR.

Application filed April 10, 1922. Serial No. 551,313.

To all whom it may concern:

Be it known that I, WILLIAM H. POOLE, a citizen of the United States, residing at Portland, in the county of Multnomah and State of Oregon, have invented certain new and useful Improvements in Indicators, of which the following is a specification.

This invention relates to indicators, and the primary object of the invention is to provide a novel means for determining in a convenient and expeditious manner, whether or not guests of a hotel, apartment house or the like, are in their rooms.

In most hotels, the presence of guests in their rooms is generally indicated by the absence of their keys from their mail boxes or their designated hooks on a rack or board. In case of telephone inquiry for a guest, the exchange operator must either inquire of the clerk or examine the mail box of the guest to see if the key is in place or send up to the guest's room. In case of verbal inquiry the clerk at the desk must examine the mail or key box or send up to the guest's room.

A prime object of the invention is the provision of an indicator board having electrical connection with the mail key boxes of a hotel or the like, each of the mail and key boxes having novel means for closing a circuit through the indicating board, when a key is withdrawn therefrom.

A further object of the invention is the provision of an indicator board embodying indicator means for each mail or key box, such as an electric lamp, buzzer or the like, the board being so disposed that the same can be readily seen by the clerk or telephone operator of the hotel, each of the mail or key boxes having circuit opening and closing means incorporated therewith and connected with its respective indicating means of the indicating board the circuit opening and closing means being adapted to be actuated upon the withdrawal or placing of a key from or into its mail or key box, the indicator board having a master switch, so that the entire circuit through the indicator board can be closed or opened when the clerk or telephone operator desires to see if certain guests are in or out of their rooms.

A further object of the invention is the provision of a means for incorporating each of the circuit closers with each of the mail or key boxes, each of the circuit closers including a metal shelf for the key having a resilient tongue struck up therefrom, the

tongue being normally adapted to engage a contact terminal interposed in the circuit of the indicating means for the mail and key box on the indicator board, the spring tongue being adapted to be depressed out of engagement with the contact terminal when the key is placed on the key shelf.

A still further object of the invention is the provision of a novel indicator of the above character, which is durable and efficient in use, one that is simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a fragmentary section through the mail or key box of a hotel, showing the improved indicator connected therewith, the indicator board and circuit being shown diagrammatically.

Figure 2 is a fragmentary front elevation of the letter or key box showing the invention applied thereto.

Figure 3 is a detail top plan view of one of the key shelves removed from its letter or key box.

Figure 4 is a detail fragmentary section through one of the mail or key boxes taken on the line 4-4 of Figure 1.

Referring to the drawings in detail, wherein similar reference characters designate corresponding parts throughout the several views, the letter A generally indicates the mail or key boxes of a hotel or similar establishment, and B the improved indicator applied thereto.

As shown, the letter or key box A is divided by transverse and vertical partitions 5 and 6 into a plurality of independent mail or key boxes or pigeon holes 7.

Each of the independent mail or key boxes or pigeon holes 7 are numbered consecutively in the usual manner, as shown at 8. These numbers conform to the numbers of the rooms in the hotel.

The improved indicating device B includes an independent circuit closer C for each of the mail or key boxes or pigeon holes 7 and an indicator board, upon which are disposed suitable indicating devices D. These indicating devices D have been

shown, by way of example to be electric lamps, and these lamps can be numbered consecutively as at 9, and these numbers conform of course, to the numbers on the mail or key boxes or pigeon holes 7. The indicator board is connected by means of suitable wires E, which will be hereinafter more fully described with each of the circuit opening and closing devices C.

10 In order to accommodate the electric wiring and to make the boxes of a neat and attractive appearance, the upper wall 10, of each mail or key box or pigeon hole 7, is provided in spaced relation thereto with a 15 horizontally disposed partition 11, which defines a space 12, in which the wires can be inserted. At the front of each mail or key box or pigeon hole 7, is disposed a facing strip 13, so as to hide the space between the top wall 10 and the partition 11 of each 20 of the boxes or pigeon holes.

Each of the circuit closing devices C includes essentially a key shelf 15, which is 25 preferably formed of electric conducting material such as sheet brass or the like, and this shelf is substantially U-shaped in cross section, as clearly shown in Figure 4 of the drawings, and includes a body portion 16, the upstanding flanges 17, and the attaching flanges 19, which can be secured to the partition 11, by means of fastening elements, such as screws 20.

The body portion 16 of each of the key shelves 15 has struck up from the same, a 30 resilient contact making and breaking tongue 21. Owing to the resilient inherency of the metal, the resilient tongue 21 is normally adapted to engage a contact bolt 22, which is also utilized as a binding post as 35 will be hereinafter more fully described. The contact bolt or binding post 22 is secured in any preferred manner to the partition plate 11 of the boxes or pigeon holes. The body portion 16 of each key shelf is 40 also provided with a second binding post 23.

The electric connecting means E includes 45 a pair of line wires 25 and 26, which can lead to any suitable source of electrical energy, such as a battery 27. As clearly shown in the drawings, the line wire 25 is electrically connected to the indicating devices D by suitable branch wires 28. The other contacts of the devices have connected thereto wires 29, which extend to the binding posts 22 of their respective boxes or 50 pigeon holes 7. The line wire 26 has electrically connected thereto branch wires 30 which lead to the binding posts 23 of the pigeon holes or boxes 7. While I have 55 shown the wires 30 connected by binding posts 23, to the shelves 15, it is to be understood that the same can be connected thereto in any other way such as by solder or the like.

Either one of the line wires 25 or 26 may 65 have a master switch interposed therein, and as shown the wire 25 is provided with a switch 31 and when the switch is closed, the circuit through the indicating lamps D may be closed when the resilient tongues 21 are 70 in engagement with their binding posts 22.

In operation of the improved device, when a key, which has been indicated in the drawings by the reference character F is inserted 75 on its key shelf, the tongue 21 will be depressed as clearly shown in Figure 1 of the drawings, and thus move the tongue out of engagement with its binding post 22, thus breaking the circuit through an indicating lamp controlled by the circuit closing and opening device incorporated with the mentioned pigeon hole or mail or key box 7. When a key is withdrawn, however, from its shelf, the tongue 21 will spring upward into engagement with the binding post 22 and 80 thus close the circuit through its indicating lamp providing the switch 31 is closed. Now, when it is desired to see if a certain guest is in his room, the clerk or telephone operator closes the switch 31 and if any of 85 the keys of the guests are not in their mail or key boxes, the indicating lamps of the mentioned mail or letter boxes will be illuminated, thus indicating at once which guests are in their rooms, and the lamps which do not light indicating which guests are out.

From the foregoing, it can be seen that a 90 novel indicating device has been provided, of exceptionally simple and durable construction, by means of which a person can be 95 at once informed, whether certain guests are in or out of their rooms, without necessitating telephoning to their rooms or examining the mail or key boxes.

Changes in details may be made, without departing from the spirit or scope of this invention; but I claim:

1. In a circuit closer, a support of non-conducting material, a conductor engaging binding post carried by said support, a shelf forming metal plate positioned beneath said support and having its side portions provided with upwardly extending attaching flanges secured to said support, a tongue being struck from said plate between the flanges and intermediate the ends of the plate and bent to extend upwardly and normally engage said binding post, and means for connecting a conductor with said plate, insertion of an article between the plate and support with a portion of the article extending between the support and tongue serving to move the tongue out of engagement with the binding post.

2. In a structure of the character described, a supporting strip of insulating material having an opening provided therein, a

resilient metallic plate positioned beneath said strip and having its side portions bent to provide upstanding flanges having outward portions secured to the under face 5 of said supporting strip, said plate between the side flanges being cut to provide a longitudinally extending resilient tongue extending upwardly from said plate and disposed between the plate and strip, a binding post

in the opening formed in said strip and having its lower end disposed for engagement by said tongue when the tongue is in its normal position, said tongue being adapted to be moved out of engagement with said binding post by an article inserted between the tongue and strip, and a binding post carried by said plate. 10 15

WILLIAM HENRI POOLE.
